US00D551911S

(12) **United States Design Patent** (10) **Patent No.:** **US D551,911 S**
Hayes et al. (45) **Date of Patent:** **** Oct. 2, 2007**

(54) **CONTAINER**

(75) Inventors: **Thomas J. Hayes**, McHenry, IL (US);
Scott D. Brown, Winthrop Harbor, IL (US); **H. Bernard Kirkland**, Lindenhurst, IL (US)

(73) Assignee: **Pactiv Corporation**, Lake Forest, IL (US)

(**) Term: **14 Years**

(21) Appl. No.: **29/223,338**

(22) Filed: **Feb. 11, 2005**
